UNITED STATES PATENT OFFICE.

RALPH V. L. HARTLEY, OF EAST ORANGE, NEW JERSEY, ASSIGNOR TO WESTERN ELECTRIC COMPANY, INCORPORATED, OF NEW YORK, N. Y., A CORPORATION OF NEW YORK.

SIGNALING METHOD AND SYSTEM.

Application filed December 24, 1920. Serial No. 432,984.

This invention relates to signaling systems and more particularly it relates to multiplex signaling systems.

One object of this invention is to produce a signaling system wherein a single transmission line may be employed to transmit simultaneously a plurality of messages, such as telephone messages, for example. Another object of this invention is to provide an improved type of repeater for use in signaling systems wherein it is desirable to repeat the signals before impressing them upon the receiving apparatus. Other objects will be apparent from the detailed description hereinafter given.

The preferred embodiment of this invention, by means of which multiplex transmission is obtained, comprises a signaling system in which apparatus, such as telephones, are employed at the transmitting stations for recording the messages and re-transmitting them to the outgoing line and at the receiving stations for recording the messages and subsequently reproducing them so that they can be impressed on a telephone receiver for example.

The method by which multiplex transmission by means of telephone tapes is obtained, consists briefly in recording each message on a separate telephone tape and reproducing short segments of each message in turn, the reproductions being effected at a velocity as many times greater than that of the velocity of recording as there are messages to be transmitted, thereby permitting all the conversations to be reproduced in a single outgoing circuit without overlapping.

In the mechanism hereinafter described for carrying out this method for the simultaneous transmission of two messages, the telephone magnets are stationary. Each tape at the transmitting station moves past its recorder continuously and past its reproducer intermittently. The tape moves by its reproducing magnet with twice the velocity it has past its recording magnet and since means are provided for insuring that when one tape is moving past its recorder the other is at rest and vice versa, it follows that both messages may be transmitted on the same outgoing line without overlapping. At the receiving station, similar apparatus are provided except that

each tape passes the recorder intermittently and continuously passes its reproducer. Each reproducer may be connected in circuit with a receiving device such as a telephone receiver.

For operating the telephones at maximum efficiency the following conditions should be obtained. First, the impedance of each of the recording or reproducing magnets should be substantially equal to the impedance of the line to which it is connected; second, magnetic leakage should be reduced to as low a value as possible; third, the reproducing magnet should be of considerably higher reluctance than its associated recording magnet; and fourth, it is preferable to employ a broad tape of high coercivity instead of a wire.

This invention will be better understood by reference to the following detailed description, taken in connection with the accompanying drawings which represent this invention embodied in a multiplex telephone system wherein two messages may be transmitted simultaneously over the same line.

Referring to the drawing, 10 is a signal transmission line which terminates at one end in a three limb induction coil 11 and an artificial line or balancing network 12 and terminates at its other end in a three limb induction coil 13 and a balancing network 14. The midpoints of the two windings of transformer 13 included serially in line 10 are connected by leads 15 and 16 to the coils of the reproducing magnets 17 and 18, which magnets are adapted to impress on line 10 amplified currents which have been recorded on the telephone tapes 19 and 20 by the two telephone transmitters 21 and 22 respectively. The signaling currents impressed on line 10 by the reproducing magnets 17 and 18 are impressed at the other end of the line by the third winding 25 of the three limb induction coil 11 upon the two recording magnets 26 and 27 whereby the messages are recorded on the telephone tapes 28 and 29 and received by the telephone receivers 30 and 31 respectively. Block 33 is intended to represent transmitting apparatus similar to that associated with station A for transmitting signals from station B to station A, and block 34 is intended to represent receiving

apparatus for station A similar to the receiving apparatus for station B.

The arrangement of this invention by means of which messages impressed on line 10 from telephone transmitters 21 and 22 may be sent out simultaneously over line 10 and received respectively by the two receivers 30 and 31 at station B, may be explained as follows:

- 10 The telegraphone tape 20, on which messages from transmitter 22 are recorded by the recording magnet 35, is adapted to move by the recording magnet continuously and by its reproducing magnet 18 intermittently.
- 15 This continuous operation of part of the tape 20 and the intermittent operation of other parts of the tape 20 are obtained by having mounted on a shaft 36, a disk 37 which may be continuously rotated by a suitable motor 38. Disk 37 is provided, around its periphery, with a plurality of pins 39 which are adapted to engage in slots in a portion of the tape 20 (not shown) whereby the tape is continuously pulled towards 25 disk 37 and away from the recording magnet 35.

At the particular instant shown in the operation of the arrangement, the tape 20 is prevented from moving past the reproducing magnet 18 on account of a movable pin 40 being held in a slot of the tape by a cam 41 mounted on shaft 36. In order to store up the amount of tape passed on by disk 37 until the time the tape is permitted to move 35 past reproducer 18, a drum 43 is provided which, by means of a suitable spring action, keeps taut a wire or tape 44 which is fastened at one end to the shaft of a pulley 45 around which the telegraphone tape passes.

- 40 The wire or holding tape 44 should be of considerable length and, as the telegraphone tape passes the disk 37, the excess portion of the tape may be stored up by the winding up of the wire 44 on drum 43. As soon, 45 however, as cam 41 allows pin 40 to be released from engagement with the tape 20 by a spring action (not shown), wire 46 by suitable spring action, will be wound on a drum 47 whereby pulley 48 serves to pull 50 the tape 20 past the reproducing magnet 18 until such a time as cam 41 again causes the insertion of pin 40 in a slot of the telegraphone tape. The spring action of drum 43 should be stronger than that of drum 43 55 in order that the pulley 48 will be effective to pull the telegraphone tape past the reproducing magnet. In order to regulate the speed with which the telegraphone tape passes the reproducing magnet 18, a cam 49 60 is mounted on shaft 36. This cam 49 has pins mounted on its periphery which are adapted to engage with the slots in the telegraphone tape whereby the tape 20 will not be allowed to pass the recording magnet 18 65 at a speed greater than the speed of rotation

of cam 49. Cam 49 for the specific embodiment shown should be of such a size as to permit the tape 20 to be pulled past the reproducing magnet 18 at a speed twice the speed the tape is passing the recording magnet 35.

After pin 40 has been pushed in a slot of the telegraphone tape by cam 41, the motion of the tape past the reproducing magnet 18 is stopped and the excess tape passing the disk 37 is stored up again by the retraction of pulley 45 by drum 43. Cam 41 on completing another half cycle will allow pin 40 to be disengaged again and permit the retraction of pulley 48 to pull the telegraphone tape past the recording magnet and store the excess tape between the rollers 50 and 51 by the retraction of the pulley 48.

It follows, therefore, by the arrangement above described, that the telegraphone tape 20 is continually passing its recording magnet 35 and is passing its reproducing magnet only half the time but at twice the speed it passes its recording magnet. 53 represents a suitable magnet for destroying the magnetic record on the tape 20 after it has passed the reproducing magnet 18 and before it reaches the recording magnet 35 again. Reproducing magnet 18 will, therefore, impress on line 10, signals from the transmitter 22, but the line 10 will be actually employed for the transmission of the signals only one half the time since when tape 20 is at rest with respect to the reproducing magnet 18, no signaling currents may be impressed on line 10 from the telephone transmitter 22.

The apparatus associated with the telegraphone tape 19 are similar to that associated with the tape 20 except that the cams for the tape 19 maintain tape 19 at rest with respect to its reproducing magnet 17 when tape 20 is passing its reproducing magnet 18, and permits tape 19 to pass its reproducing magnet when tape 20 is at rest with respect to its reproducing magnet. To this end, cam 53 is mounted on shaft 36 so that the part of its periphery bearing the pins 54 is at an angle of 180° with the corresponding portion of cam 49. Similarly, the enlarged portion of cam 55 is 180° from the corresponding portion of cam 41.

The reproducing magnets 17 and 18 as shown, are connected serially in line 10 and since means, as above described, are provided for preventing the operation of one reproducing magnet when the other is operated, it follows that the two messages from telephone transmitters 21 and 22 are impressed on line 10 without any overlapping.

If telephone receiver 31 is the receiver at station B which is desired to receive signals from transmitter 22 of station A, the apparatus associated with telegraphone 29 should be similar to that associated with 130

tape 20 except that the position of the reproducing and recording magnets should be reversed,—that is, the apparatus should be so arranged that the tape 29 passes its recording magnet intermittently and passes its reproducing magnet continually. As shown in the drawing, the cam 60 is about in position to allow the retraction of pin 61, whereby tape 29 may be permitted to start passing recording magnet 27 at the instant pin 40 at station A is retracted to permit the passing of tape 20 past the reproducing magnet 18. In order to insure that tapes 20 and 29 are started and stopped simultaneously, motors 38 and 63 should be synchronized by suitable arrangements, not shown. The synchronizing apparatus of course should take into account the actual time of transmission between the transmitting and receiving stations.

As soon as the retraction of pins 40 and 61 occurs, which permits the passing of tape 20 past the reproducing magnet 18 and the passing of tape 29 past the recording magnet 27, the message from telephone transmitter 22 is recorded on tape 29 by the magnet 27 and since the tape 29 is passing its recording magnet at a speed twice the speed it is allowed to pass the reproducing magnet 64, the excess tape is stored up by the retraction of pulley 65. The tape 29 which is continually passing reproducing magnet 64 causes the production in the telephone receiver 31, of the message transmitted from transmitter 22 of station A. At the time tape 29 is at rest with respect to the reproducing magnet 27, and the excess tape stored up by pulley 65 is running past the reproducing magnet 64, the pulley 66 is being retracted whereby the excess tape is stored up between the disk 67 and the roller 68 so that the tape will be ready for the next time the cams allow the tape 29 to pass the recording magnet 27.

It is to be noted that since tape 29 passes its recording magnet 27 while the tape 20 is passing its reproducing magnet 18, it follows that tape 29 is at rest when tape 19 of station A is passing its reproducing magnet 17 whereby signals from transmitter 21 are impressed on the transmission line 10. It therefore follows that the signals from transmitter 21 are not recorded on the tape 29. The cams associated with the telegraphone tape 28, however, should be so arranged that tape 28 starts to pass its recording magnet 26 at the same time tape 19 starts to pass its reproducing magnet 17. The signals impressed on transmission line 10 by the reproducing magnet 17 will therefore, by the recording magnet 26 be recorded on the telegraphone tape 28 whereby the associated reproducing magnet 17 is adapted to impress on telephone receiver 30 the signals from telephone transmitter 21.

The above described apparatus for obtaining the simultaneous transmission of two messages over the same transmission line may be obviously employed for the simultaneous transmission of any number of messages. In the general case wherein a plurality of messages are to be transmitted simultaneously, each tape at the transmitting station will be allowed to pass its recording magnet continuously and will pass its reproducing magnet intermittently at a speed as many times greater than that of its speed past the recorder as there are messages to be transmitted. Similarly at the receiving station each telegraphone tape should be moved past its recording magnet intermittently at a velocity as many times greater than that of the velocity of reproducing as there are messages to be received.

In order to secure maximum efficiency of operation of a telegraphone the following conditions should be obtained; first, the impedance of each reproducing or recording magnet should be approximately equal to that of the line with which it is associated, for example, recording magnet 35 should have an impedance approximately equal to the impedance of the battery 71 and the transmitter 22; second, low magnetic leakage for each magnet should be obtained by having for example, all magnetic paths as nearly closed as possible, and by having no abrupt changes in the cross section of the magnetic circuit at any point; third, the telegraphone tape should be of high coercivity, for example, material such as steel should be employed; fourth, the reluctance of each reproducer should be high with respect to the reluctance of its associated recorder; fifth, the telegraphone wire should preferably be a broad tape of appreciable thickness and be preferably run at as high a speed as is practicable.

What is claimed is:

1. The method of signaling which comprises periodically transmitting to a signaling line segments of speech signals from a source at a greater speed than received from said source, and periodically and alternately transmitting to said line segments of speech signals from another source at a greater speed than received from said other source whereby the segments of speech signals from both sources are transmitted over said line without overlapping.

2. The method of signaling which comprises producing continuous speech signal records at a fixed rate from a number of sources, and in periodically transmitting signal currents in segments from each of said records over the signaling line at a uniform rate greater than they are recorded on the signal records, said segments being transmitted in a predetermined sequence whereby said line is only intermittently em-

- ployed for the transmission of speech signals from any one source.
3. The method of signaling which comprises impressing speech current signals upon a device, dividing said signals into segments, intermittently transmitting to a line said segments at a greater speed than they were impressed on said device, impressing other signaling currents upon a second device, dividing said other currents into segments, and intermittently transmitting to said line the segments of said other signaling currents at a speed greater than they were impressed on said second device, said second signals being impressed on said line at times when said line is not being employed in the transmission of said first signals.
4. The method of signaling from a plurality of sources which comprises recording separately at a certain speed speech signals from each of said sources, and intermittently reproducing segments of speech signals from each source at a greater speed than the speed of recording in such a manner that all of said signals may be impressed upon a transmission line without overlapping.
5. The method of signaling from a plurality of sources which comprises separately recording at a certain speed the speech current signals from each of said sources, and intermittently reproducing in an outgoing line speech current signals corresponding to each of said sources at a greater speed than the speed of recording, the reproduction of said signals corresponding to each source being performed at times when said line is not responsive to signals from said other sources.
6. The method of signaling which comprises reproducing speech current signals from each of a plurality of sources, impressing the signals from each source upon a device whereby the signals are translated into a form other than that of electric waves, and subsequently translating segments of signals from each of said sources back to the form of electric waves intermittently and at a speed of translation greater than the speed of said first translation.
7. The method of impressing speech current signals from a plurality of separate sources upon the same transmission line which comprises causing the signaling currents from each source to produce at a desired speed a record of said signals, subsequently intermittently causing one of said records to produce at a greater speed signaling currents in said transmission line corresponding to one of said sources, and intermittently causing another of said records to produce signaling currents corresponding to another source in said transmission line at times when signals corresponding to said

first source are not being impressed thereon.

8. The method of impressing signals from a plurality of individual sources upon a common transmission line which comprises causing the signaling currents from each source to produce at a desired speed a magnetic record of said signals, subsequently intermittently causing one of said magnetic records to produce at a greater speed signaling currents in said line corresponding to one source, and intermittently causing another of said magnetic records to produce signaling currents corresponding to another source in said transmission line at times when signals corresponding to said first source are not being impressed thereon.

9. The method of signaling between a plurality of individual transmitters simultaneously operated and individual receivers, said transmitters and said receivers being connected by a common transmission line which comprises intermittently impressing on said line signaling currents from one transmitter, impressing on said line signaling currents from said second transmitter at times when said line is not receiving signals from said first transmitter, and maintaining said receiver connected to said line continuously throughout the period of said signaling but rendering one of said receivers responsive to currents in said line only when signaling currents from said first transmitter are being impressed on said line, and rendering a second receiver responsive to currents in said line only when signaling currents from said second transmitter are being impressed on said line.

10. A multiplex speech signaling system comprising a transmitting station, a receiving station, and a transmission line therebetween, said transmitting station comprising sources of voice current signals, means for making continuous records of said signals at a desired speed, means for intermittently impressing on said line segments of signaling voice currents produced by said continuous records, said segments produced from the different records being impressed alternately on the line and the voice currents comprising the segments being transmitted at a speed greater than the speed of recording, said receiving station comprising means for intermittently making records of the received signal segments, receiving devices, and means for continuously impressing on said devices currents produced by said records at the receiving station and at a speed corresponding to the speed of recording at said transmitting station.

11. A signaling system comprising a transmitting station, a receiving station, a transmission line connected therebetween, said transmitting station comprising a source of signals, means for continuously making a magnetic record of the signals from said

source at a desired speed, means for causing said magnetic record to intermittently produce in said line the signaling currents at a speed greater than the speed at which said record was made, said receiving station comprising means for intermittently making a magnetic record of said signaling currents, a receiving device, and means for causing said last mentioned magnetic record to impress continuously on said device the signaling currents at a speed corresponding to the speed at which said first magnetic record was made.

12. In a receiving system, a tape of magnetic material, a source of current, a recording device associated with said source and said tape whereby a magnetic record is produced on said tape corresponding to the currents from said source, a signal line, a reproducing device associated with said tape and said line whereby the magnetic record on said tape varies the current in said line, and means for causing said tape to pass said recording device continuously and to pass said reproducing device intermittently.

13. In a receiving system, a line, an endless tape of magnetic material, a recording device associated with said line and said tape whereby a magnetic record of the currents in said line is made on said tape, a receiving device, a reproducing device associated with said receiving device and said tape whereby the magnetic record on said tape varies the current through said receiving device, and means for causing said tape to pass said recording device intermittently and pass said reproducing device continuously.

14. In a multiplex signaling system, a plurality of transmitting stations, a plurality of receiving stations, a common transmission line therebetween, each of said transmitting stations comprising an endless tape of magnetic material, a source of signals, a recording device associated with said source and said tape whereby the currents from said source produce a magnetic record on said tape, a reproducing device associated with

said line and said tape whereby the currents in said line are varied in accordance with the magnetic record of said tape, means for causing said tape to pass said recording device continuously and pass said reproducing device intermittently, said means for each transmitting station being so related to said means for the other transmitting stations that the tape at one transmitting station passes its reproducing device only when the other tapes are at rest with respect to their reproducing devices, each of said receiving stations comprising a receiver, and means for making each of said receivers individually responsive to signals from one of said transmitting stations.

15. In a signaling system, a signal line, a plurality of transmitting stations associated with said line, each of said transmitting stations comprising a source of signals, an endless tape of magnetic material, slots in said tape, a recording magnet associated with said source and said tape, a reproducing magnet associated with said line and said tape, a plurality of disks, means for rotating said disks, one of said disks having pins spaced thereon throughout its entire periphery, said disk being so positioned that said pins cooperate with said slots to produce a continuous movement of said tape, a second of said disks having pins spaced on that fractional portion of its periphery equal to its circumference divided by the number of transmission stations desired to be operated simultaneously, said second disk being so positioned that the pins on the said disk cooperate with the slots in said tape to control the movement of said tape, said recording device being associated with that part of the tape adjacent said first disk, and said reproducing device being associated with that part of the tape adjacent said second disk.

In witness whereof, I hereunto subscribe my name this 18th day of December A. D., 1920.

RALPH V. L. HARTLEY.
